PHONOGRAPH

Donald I. Coney, Detroit, Mich., assignor to N.
Marshall Seeburg, Chicago, Ill.

Application November 19, 1936, Serial No. 111,607

8 Claims. (Cl. 274—10)

This invention relates to phonographs and more particularly to dual phonographs which comprise a manually controlled phonograph and an automatic phonograph.

The general nature of the invention will be more readily understood by a brief description of a preferred embodiment of the invention. For example, I may take a phonograph of well-known type which is controlled by the insertion of one or more coins. Such phonographs normally have a plurality of records from which a customer may select one or any other number. By inserting a corresponding number of coins in a coin chute the records thus selected will be played. If no records are selected, the phonograph will play a sequence of records. Such phonographs are well known and they normally remain idle a large part of the time.

According to the present invention I provide an auxiliary phonograph which is brought into operation automatically, for example, by means of a time switch, and this auxiliary phonograph may make a suitable announcement. For example, it may give a short advertising talk. The auxiliary phonograph is connected to the same amplification and reproducing system as the main phonograph. Means are provided whereby one phonograph is prevented from coming into operation when the other phonograph is playing. If the main phonograph is playing a selection at a time when the time switch closes, that selection is not interrupted, but the signal is stored and immediately at the end of that selection the auxiliary phonograph comes into operation and gives the talk due at that time. This occurs whether or not the main phonograph is set for further selections. After the talk by the auxiliary phonograph, the playing of such selections as have been paid for on the main phonograph is resumed. If a customer inserts a coin or coins into the main phonograph while the auxiliary phonograph is playing, the main phonograph does not start to play until the termination of the talk by the auxiliary phonograph.

The invention will be more completely understood by the following description of a preferred embodiment thereof, taken in conjunction with the accompanying drawing, which is a diagrammatic illustration of a machine embodying the invention.

The mechanism on the left-hand side of the drawing represents schematically the fundamental parts of a conventional automatic phonograph. The mechanism on the right-hand side of the drawing represents the auxiliary elements

which are added thereto in order to attain the objects of the present invention. The manner in which two units are connected together by wiring is, of course, readily apparent from the drawing.

The main phonograph comprises a turntable 10 which is supported on the upper end of a long spindle 11. This spindle is driven by a gear 12 which is splined on the spindle so that the spindle may move up and down. The gear 12 is driven from a main motor 13 which operates when the main phonograph is in operation.

The main phonograph includes a pick-up 14 and means for supporting a plurality of records 15 between the lowermost position of the turntable 10 and the normal position of the pick-up 14. The phonograph may be provided with means (not shown) for introducing a selected record or a selected sequence of records 15 into alignment with the turntable 10. After each record is thus presented, the linkage 16 is operated so as to force the turntable 10 upwardly to bring the record into cooperation with the pick-up 14. After the termination of the playing the turntable descends, the record 15 is taken therefrom and returned to its position in the stack. At the same time the pick-up 14 is returned to its initial playing position for engagement with the next record.

The upward and downward movements of the turntable 10 are accompanied by half rotations of a shaft 17. This shaft carries an arm 18 on which is pivotally mounted a dog 19. This dog 19 carries a pin 20 and is normally held in the position shown by a spring 21. The shaft 17 rotates in the direction indicated by the arrow and near the end of the half turn which it performs during the descent of the turntable 10, the pin 20 engages a stationary abutment 22' which causes an angular deflection of the dog 19 with respect to the arm 18, against the tension of the spring 21. When the pin 20 clears the abutment 22' the spring 21 causes the dog 19 to flip rapidly into the position shown in the drawing. In so doing the pin 20 engages one of the teeth of a ratchet wheel 22 and causes it to rotate in counterclockwise direction. The ratchet wheel 22 is biased by a spring 23 so that it tends to rotate in the opposite direction. It is prevented from rotating in this direction by an escapement 24.

The phonograph is provided with a conventional coin slide 25 which is so arranged that each coin which is inserted into the machine by the coin slide closes a switch 26. The switch 26, together with a suitable resistance, for example,

relay lamp 27, is in series with an electromagnet 28. This circuit is connected to the 110-volt power lines 29 and 30 by means of conductors 104 and 105. The escapement 24 carries an armature 31 in cooperative relationship with the electromagnet 28. When a coin is inserted, the switch 26 is closed, the electromagnet 28 is energized and the escapement 24 permits the ratchet wheel 22, under the influence of the spring 23, to move one tooth in the clockwise direction. If a successive number of coins is inserted in the coin slide 25, the ratchet wheel 22 will rotate a corresponding number of teeth, within the capacity of the device.

15 The ratchet wheel 22 carries a pin 32 which is adapted to engage the end of a pivotally mounted arm 33. The arm 33 carries contacts 34 and 35 which are adapted to cooperate with stationary contacts 36 and 37 respectively, which are connected to power line 30 by conductor 107. The arm 33 is biased by a spring 42 so that it normally tends to move the contacts 34 and 35 into engagement with the contacts 36 and 37. The normal initial position of the ratchet wheel 22 is 25 that shown in the drawing. In this position of the ratchet wheel the pin 32 holds the contacts 34 and 35 separated from the contacts 36 and 37.

When a coin is inserted the switch 26 is closed and the ratchet wheel 22 is turned one tooth in 30 the clockwise direction. As a result of this movement, the pin 32 separates from the switch arm 33 and the contacts 34 and 35 make engagement with the contacts 36 and 37. The insertion of successive coins merely causes the ratchet wheel 35 22 to move a corresponding number of teeth steps in the clockwise direction. As indicated above, each time the turntable 10 descends the pin 20 causes the ratchet wheel 22 to move one step in the counter-clockwise direction. Consequently, 40 after a number of records 15, corresponding to the number of coins inserted, has been played the pin 32 moves the contacts 34 and 35 away from the contacts 36 and 37, breaking the operating circuit of the main motor as will hereinafter be 45 more fully described.

The main phonograph unit includes an amplifier 38 and a loud speaker 39.

The spindle 11 carries a disc 40 which is adapted, in the lowermost position of the turntable 10, 50 to move two contacts 41 together. In its lowermost position the disc 40 also forces two contacts 43 together. Each lead of the pick-up 14 is connected to one of the contacts 41. The result is that when the turntable 10 is in its lowermost 55 position the pick-up 14 is shorted by the contacts 41.

The auxiliary unit comprises a turntable 44 on which is located a single record 45. The record 45 may have a suitable number of short talks 60 recorded thereon. For example, it may have four short talks, each of somewhat less than a minute's duration. The turntable 44 is driven by a motor 46, when the latter is energized, and a pick-up 47 is provided for cooperation with the record 45. The motor 46 also drives very slowly a large gear wheel 47'. This gear wheel preferably makes one revolution during the playing of the record 45; that is, during the four successive talks which are recorded on that record.

70 The gear 47' carries a pin 48 which is adapted to engage an arm 49 which extends radially from a vertical shaft 50. This shaft is mounted for free rotation about its longitudinal axis and has pivoted to its upper end the tone arm 51 which 75 carries the pick-up 47. The playing of the record

45 causes the player arm 51 to move inwardly towards the center of the record. This brings the arm 49 into the path of the pin 48 so that the final rotation of the gear 47' causes the tone arm 51 to move to initial playing position. During 5 this movement of the tone arm the same is held elevated by a rod 52. This rod is mounted for longitudinal movement and carries at the upper end a bar 53 which is adapted to engage the underside of the tone arm 51. It will thus be 10 seen that when the rod 52 is held in its uppermost position, the tone arm 51 may be slid back to a point above initial playing position without injury to the record 45.

On its uppermost side the gear 47' is provided 15 with four cams 54 which are adapted to engage a roller 55 on the lower end of the rod 52. This rod is held against rotation and for this purpose it may suitably have a square cross-section and be guided in square openings in the frame of the 20 auxiliary phonograph. The cams 54 are so located on the gear 47' that the tone arm 51 is elevated at the end of each talk on the record 45. After the playing of the last talk, the appropriate cam 54 lifts the shaft 52 and while it is thus raised 25 the pin 48 engages the pin 49 and returns the pick-up 47 to a point above initial playing position.

The rod 52 carries a disc 56 which is adapted, when the rod 52 is moved upwardly, to close a 30 pair of contacts 57. The contacts 57 are connected to the leads of the pick-up 47 so that the pick-up 47 is short-circuited when the tone arm is raised from the record 45.

The auxiliary unit also comprises a time switch 35 58. The time switch 58 may comprise a conductive arm 59 which rotates once an hour and comes into engagement with conductors 60 at suitable intervals, for example, every quarter of an hour. The arm 59 may suitably be connected to the 40 power lead 30 by a conductor 102 and the contacts 60 may be connected through a suitable resistance, for example, a relay lamp 61, by a conductor 103 to one side of an electromagnet 62. The other side of the magnet 62 is connected to 45 the power lead 29 by a conductor 101.

The electromagnet 62 cooperates with an armature of an escapement 63 of a ratchet 64 which is mounted for free rotation on a stationary shaft 65. The ratchet 64 is biased by a spring 66 for rotation in the counter-clockwise direction so that when the magnet 62 is energized, which occurs each quarter of an hour, the ratchet wheel 64 moves one tooth in the counter-clockwise direction under the influence of the spring 66. 55 The ratchet wheel 64 carries a pin 67 which is adapted to engage an arm 68 which carries contacts 69 and 70. The arm 68 is biased by the spring 71 so as normally to bring the contacts 69 and 70 towards stationary contacts 72 and 73. When the ratchet wheel 64 is rotated sufficiently in the clockwise direction, the pin 67 makes contact with the arm 68 and separates the contacts 69 and 70 from the contacts 72 and 73. When the electromagnet 62 is energized, the 65 ratchet wheel 64 moves the distance of one tooth in the counter-clockwise direction and the spring 71 moves the arm 68 to bring the contacts 69 and 70 into engagement with the contacts 72 and 73. The contacts 72 and 73 are connected 70 to power line 30 by a conductor 106.

Also mounted on the shaft 65 for free rotation thereon is a ratchet wheel 74 provided with a pin 75. The ratchet wheel 74 is biased for rotation in the counter-clockwise direction by a 75

spring 76. The rotation of the ratchet wheel 74 in this direction is controlled by an escapement 77 which in turn can be actuated by an electromagnet 78. The pin 75 is adapted to cooperate with a pivotally mounted arm 79 which carries a contact 80. The arm 79 is biased by a spring 81 so that it tends to move the contact 80 away from the contact 82. When the ratchet wheel 74 is rotated sufficiently in the clockwise direction, the pin 75 moves the arm 79 so as to bring the contact 80 into engagement with the contact 82. When the ratchet wheel 74 is moved in the opposite or clockwise direction, the spring 81 moves the contact 80 away from the contact 82. The contacts 80 and 82 are resiliently mounted so that they are not separated by backlash after they are brought into engagement by movement of the lever 84, as will be hereinafter described.

20 The two ratchet wheels 64 and 74 are mounted on the same shaft 65 and they are preferably located quite close together. These ratchet wheels are moved periodically in the clockwise direction by means of a common member operated from the 25 vertically moving rod 52. This rod carries an arm 83 which extends into one end of a lever 84 which is pivotally mounted on part of the rigid framework. At its outer end the lever 84 has pivotally mounted thereon a dog 85 which is similar to the dog 19 previously described. 30 This dog 85 is provided with a pin 86 which may be a relatively long pin so as to cooperate with both ratchet wheels 64 and 74.

The tension spring 87 connected to the dog 85 35 and to the lever 84 tends to hold the dog 85 with the pin 86 in position so that it may enter the path of one of the teeth of each ratchet wheel 64 and 74. A suitable abutment member 88 cooperates with a pin 86 in the same manner as did the abutment member 22' with the pin 20. 40 The tone arm 51 of the auxiliary phonograph is shown in elevated position and the pin 86 is clear of both ratchet wheels 64 and 74. Consequently, when either or both of the electromagnets 62 and 78 is or are energized, the associated ratchet wheel or ratchet wheels are free to turn one step in the counter-clockwise direction. As herein-after described, the result either immediately or eventually of this movement of the ratchet wheel 64 is that the motor 46 starts and the rod 52 drops. When this occurs the lever 84 is swung and the dog 85 is moved upwardly beyond the abutment member 88, the pin 86 slipping past the teeth of the ratchet wheels 64 and 74. When, however, the reverse movement of the lever 84 55 occurs, the pin 86 engages the abutment 88 and the spring 87 is energized. With the continued downward movement of the dog 85, the pin 86 clears the abutment member 88 and the pin 86 strikes sharply one of the teeth of each of the ratchet wheels 64 and 74, moving these ratchet wheels one step in the clockwise direction and leaving the pin 86 clear of the ratchet wheels.

One of the contacts 41 is connected directly 60 by a conductor 89 to one of the contacts 57. The other contact 41 is connected by a conductor 90 to the amplifier 38. The other contact 57 is connected by a conductor 91 to the amplifier. The pick-ups 14 and 47 are thus connected to 65 the amplifier in series, but the contacts 41 and 57, respectively, enable one pick-up to be short-circuited when the other is in operation. Thus the contacts 41 are in engagement when the main turntable 10 is in its lowermost position and the contacts 57 are in engagement when the 70

pick-up 47 is elevated out of contact with the record 45.

The contacts 36 and 37 are connected directly to the power lead 30. The contact 34 is connected by a conductor 91 to the amplifier 38 and 5 also to the contact 70. The contact 35 is connected by a conductor 92 to the contact 80. One of the contacts 43, which contacts are brought into engagement when the turntable 10 moves to its lowermost position, is connected by a conductor 93 to the contact 69. The other contact 43 is connected by a conductor 94 and a relay lamp 95 to one side of the electromagnet 78. The latter contact 43 is also connected by a conductor 96 to one terminal of the motor 46. 15 The power line 29 is connected by a conductor 97 to the other terminal of the motor 46, by a conductor 98 to the amplifier 38, by a conductor 99 to one terminal of the main motor 13, by a conductor 100 to one terminal of the electromagnet 78, and by a conductor 101 to one terminal of the electromagnet 62. 20

The operation is as follows: Assuming that the main phonograph is not operating, then the time switch 58, which may suitably be actuated by an electric clock or other suitable time-keeping mechanism, causes the conductive arm 59 to engage one of the contacts 60. In the present embodiment of the invention this occurs every quarter of an hour. The following circuit is then 25 completed: power line 29, electromagnet 62, relay lamp 61, contact 60, arm 59, conductor 102, and power line 30. The electromagnet 62 is thus energized and it operates the escapement 63 so that the pin 61 moves away from the arm 68. 30 The spring 71 now raises the contacts 69 and 70 into engagement with contacts 72 and 73. The engagement between the arm 59 and the contact 60 only exists for a short time and may be regarded as being broken forthwith. The following 35 circuit is now completed: power line 30, conductor 106, contacts 73 and 70, conductor 91, amplifier 38, conductor 98 and power line 29. At the same time a circuit is completed from power line 30, conductor 106, contacts 72 and 69, 40 conductor 93, contacts 43 (the same being in engagement owing to the lower inoperative position of the main turntable 10), conductor 94, relay lamp 95, electromagnet 78, conductor 100, and power line 29. Another branch of this last said 45 circuit passes through conductor 96, motor 46 and conductor 97 to power line 29. The result is that power current is supplied to the amplifier, the motor 46 is put into operation and the ratchet wheel 74 is permitted to move in a counter-clockwise direction, separating the contacts 50 80 and 82. These contacts are located in the circuit of the motor 13 and, consequently, it is impossible to start that motor until the contacts 55 80 and 82 are again in engagement.

The initial result of the operation of the motor 46 is that the cam 54 passes from its initial position beneath the rod 52 and permits this rod to descend. The tone arm 51 is thus allowed to descend until the needle of the pickup 47 comes 60 into contact with the playing surface of the record 45.

In the present embodiment of the invention I provide for four distinct transcriptions on the record 45. In the case that the second, third or 65 fourth transcriptions are being initiated, the tone arm 51 simply drops onto the record again at the point from which it was elevated. If, however, the auxiliary phonograph should play the first transcription, then it is necessary to 70 75

translate the tone arm 51 to initial playing position of the record. This is effected by the pin 48 coming into contact with the arm 49 and swinging the shaft 50 in the appropriate direction. While the shaft 50 is being swung, it is necessary that the tone arm 51 should be held above the record and the effective cam 54 is sufficiently long to make sure that the tone arm will not fall until after its translation.

10 It is to be noted that in the initial condition of the machine the contacts 57 are in engagement and the contacts 41 are in engagement. When, however, the rod 52 descends the contacts 57 separate and the pick-up 47 is now effectively connected to the amplifier 38. It is to be noted that as the rod 52 drops, the dog 85 is elevated past the adjacent teeth of the ratchet wheels 64 and 74, without affecting these ratchet wheels.

The transcription is now played, for example, 20 for a period of almost a minute and at the end of that time the next cam 54 proceeds to elevate the shaft 52. That elevation raises the pick-up 47 off the record, it being noted, however, that the arm 53 frictionally engages the tone arm 51 25 in such a manner that when the rod 52 is again lowered, the pick-up 47 will be placed on the record in the same position that it was before except, of course, when the tone arm has to be moved to the initial playing position on the 30 record. The elevation of the rod 52 brings the contacts 57 into engagement. As the rod 52 elevates it swings the dog 85 bodily downwardly and the pin 86, when it clears the abutment 88, 35 snaps into contact with teeth on the ratchet wheels 64 and 65. When this occurs the contacts 59 and 70 are separated from the contacts 72 and 73 and the contacts 80 and 82 are brought into engagement.

The main phonograph can now be played by 40 inserting the appropriate coins in the coin chute 25 in the manner previously described. If, however, a customer inserts a coin, or a plurality of coins, into the coin chute 25 while the auxiliary phonograph is playing, then each coin completes a circuit including power line 30, contacts 45 26, lamp 27, conductor 105, electromagnet 28, conductor 104 and power line 29. Consequently, the electromagnet is energized as many times as coins are inserted, and the ratchet wheel 22 50 moves in the clockwise direction a corresponding number of teeth. The first movement of the ratchet wheel 22 causes the contacts 34 and 35 to come into engagement with the contacts 36 and 37, respectively. The following circuit is 55 now completed: power line 30, conductor 107, contact 38, contact 34, conductor 91, amplifier 38, conductor 98 and power line 29. This circuit shunts the circuit already referred to which was completed by the engagement of the contacts 70 60 and 73. When, however, these contacts separate by the clockwise rotation of the ratchet wheel 64, the amplifier 38 remains energized for reproduction from a record on the turntable 10. At the same time a circuit is completed from 65 power line 30, conductor 107, contact 37, contact 35, conductor 92 to contact 80. However, while the auxiliary phonograph is playing the contact 80 is out of engagement with the contact 82 so that this circuit remains ineffectual 70 until the auxiliary phonograph has completed playing its particular transcription and the tone arm 51 has been elevated.

Immediately the ratchet wheel 74 is rotated one step in the clockwise direction by the dog 75 85, contacts 80 and 82 make engagement and

the circuit for the motor 13 is then completed. The result of the operation of the motor 13 is that a selected one of the records 15 is brought into alignment with the turntable 10 and that turntable rises, bringing the record into contact 5 with the needle of the pick-up 14. After the record 15 has played the turntable 10 descends, the record is taken from the turntable and replaced in the stack.

The descent of the turntable 10 is accompanied 10 by a half rotation of the shaft 17, which moves the ratchet wheel 22 one tooth in the counter-clockwise direction. The playing of records is repeated until at last the pin 32 moves the arm 33 so as to move the contacts 34 and 35 out of 15 engagement with the contacts 36 and 37. Of course, if one or more coins are inserted in the coin chute 25, the phonograph will play again for a corresponding number of times.

It is to be noted that when the turntable 10 20 is up, the contacts 43 are out of engagement with each other and, consequently, the coming of the arm 59 of the time switch 58 into engagement with one of the contacts 60 will not initiate the operation of the phonograph 44. What happens is 25 that the ratchet wheel 64 will rotate one tooth in the counter-clockwise direction and the contacts 69 and 70 will be moved into engagement with the contacts 72 and 73. The circuit previously referred to as being made through the amplifier will again be made, this circuit being in shunt relation to the existing circuit for the amplifier. However, the circuit previously referred to as being made through the contacts 69 and 72 30 will not be completed owing to the fact that the 35 turntable 10 is in its upward position and the contacts 43 are out of engagement. When, however, the turntable 10 next descends, and it may here be noted that it descends after the playing 40 of each record 15, the contacts 43 are brought into engagement, the electromagnet 78 is energized so that the contacts 80 and 82 are separated, and the motor 46 is put into operation. Owing to the separation of the contacts 80 and 82, the motor 13 cannot come into operation, irrespective of 45 the position of the ratchet wheel 22, until it completes its transcription.

Upon the completion of the transcription the contact 80 is moved into engagement with the contact 82, the contacts 69 and 70 are separated 50 from the contacts 72 and 73 and if the contacts 34 and 35 are in engagement with the contacts 36 and 37, the operation of the main phonograph is resumed until at last the contacts 34 and 35 55 are separated from the contacts 36 and 37.

It will thus be seen that I have provided the combination of a main phonograph and an auxiliary phonograph, the main phonograph being available for coin-free use in well-known manner and the auxiliary phonograph coming automatically into operation at intervals. I have provided mechanism whereby one phonograph is rendered 60 unable to interrupt the operation of the other phonograph until it has finished its playing. And 65 I have provided mechanism whereby the auxiliary phonograph is caused to interrupt, at its appropriate time or a short time thereafter, a program on the main phonograph, which program is resumed after the auxiliary phonograph has had its 70 turn.

Although the invention has been disclosed in connection with the specific details of a preferred embodiment thereof, it must be understood that such details are not intended to be limitative of 75

the invention except in so far as set forth in the accompanying claims.

Having thus described my invention, what I claim as new and desire to secure by Letters Patent of the United States is:

1. In combination, means including a pick-up for reproducing a phonograph record, manually operable means for initiating the reproduction of a record, auxiliary means including a pick-up for reproducing a phonograph record, means including a clock for automatically and periodically initiating the reproduction of last said record, means operatively associated with each initiating means and adapted to be actuated thereby for rendering the other reproducing means inoperative, an amplifier, a pick-up circuit connected thereto including said pick-ups in series, and means in each reproducing means for short-circuiting its pick-up.
2. In combination, means for reproducing a phonograph record, coin controlled means for initiating the reproduction of a record, auxiliary means for reproducing a phonograph record, means including a clock for automatically and periodically initiating the reproduction of last said record, and means operatively associated with each initiating means and adapted to be actuated thereby for rendering the other reproducing means inoperative.
3. In combination, means for reproducing a phonograph record, manually operable means for initiating the reproduction of a record, auxiliary means for reproducing a phonograph record, means including a clock for automatically and periodically initiating the reproduction of last said record, and means operatively associated with each initiating means for rendering the other reproducing means inoperative, and means on each reproducing means for rendering the other reproducing means operative.
4. In combination, means including a pick-up for reproducing a phonograph record, coin controlled means for initiating the reproduction of a record, auxiliary means including pick-up for reproducing a phonograph record, means including a clock for automatically and periodically initiating the reproduction of last said record, means operatively associated with each initiating means to render the other reproducing means inoperative, means on each reproducing means for rendering the other reproducing means operative, an amplifier, a pick-up circuit connected thereto including said pick-ups in series, and means in each reproducing means for short-circuiting its pick-up.
5. In combination, means for reproducing a phonograph record, manually operable means for setting the said means for the repro-

duction of a series of records, auxiliary means for reproducing a phonograph record, means controlling the operation of last said reproducing means, clock means adapted automatically and periodically to move last said means to operative position, and controlling means operable by the first said reproducing means adapted to initiate the operation of the auxiliary reproducing means.

6. In combination, means for reproducing a phonograph record, coin controlled means for setting said means for the automatic reproduction of a series of records, auxiliary means for reproducing a phonograph record, a control member, a clock for moving said member to operative position at definite intervals, controlling means adapted to be operated by the first said reproducing means at the end of the playing of each record, said control member and controlling means being adapted to cooperate to initiate the operation of the auxiliary reproducing means, and means actuated by the auxiliary reproducing means at the end of its playing operation for initiating the operation of the first said reproducing means.

7. In combination, a phonograph, coin controlled means for setting said phonograph for the automatic reproduction of a series of records, an auxiliary phonograph, a relay switch, a clock for closing said switch at predetermined intervals, a switch adapted to be closed by the first phonograph at the end of the playing of each record, a circuit including both said switches and adapted when closed to initiate the operation of the auxiliary phonograph, and means actuated by said circuit when closed for rendering the first said phonograph inoperative.

8. In combination, a phonograph, counting means operable in stepwise manner by the insertion of coins and operable stepwise in the opposite direction by the phonograph, a circuit for operating the phonograph, a switch in said circuit controlled by said counting mechanism, a second switch in said circuit, an auxiliary phonograph, a circuit for operating the auxiliary phonograph, a switch in said auxiliary phonograph circuit, a clock adapted periodically to close said switch, a second switch in said auxiliary phonograph circuit adapted to be closed at the end of the playing of each record by the first said phonograph, a relay operated by the closing of the last two said switches for opening the second switch of the first said phonograph circuit, and means operable by the auxiliary phonograph at the end of its playing for closing the second switch of the first said phonograph and opening the second switch of the auxiliary phonograph.

DONALD I. CONEY.

CERTIFICATE OF CORRECTION.

Patent No. 2,125,100.

July 26, 1938.

DONALD I. CONEY.

It is hereby certified that error appears in the printed specification of the above numbered patent requiring correction as follows: Page 5, first column, line 6, beginning with the numeral and word "1. In" strike out all to and including the word and period "inoperative." in line 29, constituting claims 1 and 2, and insert instead the following claims -

1. In combination, means for reproducing a phonograph record, manually operable means for initiating the reproduction of a record, auxiliary means for reproducing a phonograph record, means including a clock for automatically and periodically initiating the reproduction of last said record, and means operatively associated with each initiating means and adapted to be actuated thereby for rendering the other reproducing means inoperative.
2. In combination, means including a pick-up for reproducing a phonograph record, coin controlled means for initiating the reproduction of a record, auxiliary means including a pick-up for reproducing a phonograph record, means including a clock for automatically and periodically initiating the reproduction of last said record, means operatively associated with each initiating means and adapted to be actuated thereby for rendering the other reproducing means inoperative, an amplifier, a pick-up circuit connected thereto including said pick-ups in series, and means in each reproducing means for short-circuiting its pick-up.

and that the said Letters Patent should be read with this correction therein that the same may conform to the record of the case in the Patent Office.

Signed and sealed this 30th day of August, A. D. 1938.

Henry Van Arsdale

(Seal)

Acting Commissioner of Patents.
